SEAM PRESSING MACHINE

Alfred S. Clark, Beverly, and Edward M. Spence, Sr., Lynn, Mass., assignors to United Shoe Machinery Corporation, Flemington, N. J., a corporation of New Jersey

Application December 10, 1945, Serial No. 634,013

15 Claims. (Cl. 69—7)

1

This invention relates to machines for pressing seams formed in shoe parts, for example, the backseams of shoe uppers, and it is herein illustrated and described as embodied in a machine of the type disclosed in United States Letters Patent No. 2,419,596, granted April 29, 1947, upon the application of Edward Quinn and Fred E. Muzzey. Machines of this type are provided with a seam pressing roll of relatively large diameter and with a pair of work feeding rolls between which the pressing roll extends. A suitable support is provided for holding the work against the pressing roll and the feed rolls. The work is presented to the machine with the unfinished side, i. e., the flesh side of the leather, in contact with the feed rolls and the pressing roll.

Although machines of the character above referred to have proved satisfactory in use upon ordinary work, neither such machines nor any other, so far as applicants are aware, are entirely satisfactory for operation upon certain particular kinds of work. For example, some uppers are provided with what is known as "Hurley back stays," that is, tabs extending from one of the quarters of the shoe upper across the line of the backseam (the actual backseam being interrupted by the tab) and eventually secured to the other quarter. Such tabs present peculiar difficulties in running through the ordinary seam pressing machine. The tabs, when the work comes to the operator of the machine, are usually curled or folded back over the quarter from which they extend, with their finished surfaces exposed to damage by the feed and presser rolls. Attempts on the part of the operator to prevent such damage are rendered difficult by reason of the fact that both hands are engaged in holding the work piece. Such attempts, moreover, result in unduly slowing up the operation.

It is an object of the present invention to provide a seam pressing machine capable of operating upon uppers having Hurley back stays. In accordance with this object, a feature of the invention consists in the provision of a guide, engageable with the tab of a Hurley back stay, to bend the tab down upon the part of the upper which is opposite to that from which the tab extends, with the finished surface of the tab away from the feed and presser rolls. This tab guide may be readily shifted, by a treadle, from one position to another to adapt it to operation upon either right or left uppers; and it may, when desired, be shifted to a neutral or inoperative position.

In accordance with a further feature of the invention, the machine illustrated herein is pro-

2

vided with an improved slide which carries the work support. This slide may be moved to bring the work support out from under the seam pressing roll and away from the feed rolls to enable the operator to remove a stack of closed uppers which have accumulated around the work support.

These and other features of the invention, including certain details of construction and combinations of parts, will be described in connection with an illustrative machine and pointed out in the appended claims.

Referring now to the accompanying drawings,

Fig. 1 is a front elevation, with some parts removed, of an illustrative machine embodying the invention;

Fig. 2 is a side elevation, partly in section, of the machine shown in Fig. 1;

Fig. 3 is a plan view of the machine with certain portions removed;

Fig. 4 is a side elevation on an enlarged scale of the mechanism for driving one of the feed rolls from the presser roll shaft;

Fig. 5 is a section on the line V—V of Fig. 4;

Fig. 6 is a front view, looking in the direction of the arrow A on Fig. 2, showing the work support in relation to the pressing roll and the feed rolls;

Fig. 7 is an enlarged view, looking in the direction of the arrow A on Fig. 2, showing the seam ridge guides in relation to the work support and the feed rolls;

Fig. 8 is an enlarged front view, looking in the direction of the arrow A on Fig. 2, of the means for guiding the tabs of Hurley back stays;

Fig. 9 is an angular view showing a work piece with a Hurley back stay being introduced into the machine; and

Fig. 10 is a view similar to Fig. 9 showing the work piece further advanced in the machine.

The operating instrumentalities of the illustrative machine comprise a driven seam pressing or seam rubbing roll 10 of large diameter a, work support 12 (Figs. 1 and 2), and a pair of driven

45 feed rolls 14 and 16. A work piece W (Figs. 9 and 10) consisting of a shoe upper having two quarters stitched together to form a back seam is guided to the operating members by a seam ridge guide 18 (Fig. 2), a seam crease guide 20 in ad-

50 vance of the locality of operation, and a seam crease guide 22 positioned rearwardly of the locality of operation. An additional guide 24 which

55 may be moved from an out-of-the-way to an operative position when desired is provided for guiding the tabs of work pieces having Hurley back

stays. The work piece W, which is presented to the machine wrong side out, is shown in Figs. 9 and 10 as having such a tab T extending from one of the quarters above the seam ridge. This tab, during the operation of the illustrated machine, is loose; after completion of the seam pressing operation the work piece will be turned right side out and the tab will be stitched down upon the outside of the other quarter with its finished surface out. To avoid undue thickness of material, the quarter to which the tab is to be stitched has a notch N (Fig. 9) somewhat smaller than the tab to leave sufficient margin for stitching the tab. The seam pressing roll, the feed rolls, the seam ridge guide, and the tab guide are supported by a yoke-shaped integral bracket 26 (Figs. 1, 2 and 3) having a cross piece 28 and a pair of side members 38 and 32 which are welded (or cast integrally if preferred) at their lower ends to a base plate 34 suitable for mounting on a work bench (not shown). The work support 12 also is mounted on the base plate 34.

The seam pressing roll 10 is a narrow disk-like member having a fluted periphery. It is secured upon a shaft 36 journaled in a pair of bearings 38 (Fig. 5) adjacent to its right-hand end and a similar pair of bearings (not shown) adjacent to its left-hand end, these bearings being carried by the upper portion of the frame member or bracket 26. A pulley 40 secured upon the right-hand end of the shaft 36 is driven by a belt 42 which, in turn, may be driven from any suitable source of power to turn the roll 10 at high speed.

The feed roll 14 is secured upon one end of a shaft 44 journaled adjacent to its right-hand end in a pair of bearings 46 (Fig. 5) mounted in the upper right-hand portion of the frame member 26 and also in a bearing 48 (Fig. 1) carried by a bracket 50 depending from the cross piece 28. Between the bearings 46 the shaft 44 is slidably keyed in a worm wheel 52 which meshes with a worm 54 secured upon a sleeve 56 (Fig. 4). The shaft 44 is free to move axially, but axial movement of the worm wheel 52 is prevented by the engagement of the opposite ends of the bearings 46 with the hub of the worm wheel. A stationary shaft 58 secured in the frame member 32 supports a set of bearings 60 and 62 upon which the sleeve 56 is freely rotatable about the axis of the shaft 58. Also secured upon the sleeve 56 and rotatable in unison with the worm 54 is a spiral gear 64 which meshes with a spiral gear 66 keyed upon the shaft 36 between the right-hand set of bearings 38. Through the gearing above described the shaft 44 is driven, at a considerably reduced speed, from the shaft 36. The frame member 26 is shaped to provide a housing 68 for these gears, which housing is closed by a cover plate 70. Surrounding the shaft 44 outside the housing 68 is a coil compression spring 72 (Fig. 1) bearing at its right-hand end, through a thrust washer, against the adjacent wall of the housing 68 and at its left-hand end, through a thrust washer, against a collar 74 adjustably secured by a setscrew to the shaft 44. Movement of the shaft 44 toward the left under the influence of the spring 72 is limited by a collar 76 engageable with the bearing 48 and adjustably secured to the shaft by a setscrew.

The feed roll 14 is mounted upon the right-hand end of a shaft 78 (Fig. 1) journaled in a bearing 80 carried by a bracket 82 depending from the cross piece 28 and also in a set of bearings contained within a housing 84 formed in the upper left-hand end of the frame 26. The shaft

78 is driven from the shaft 36 by a set of gears within the housing 84 similar to the gears, already described, within the housing 68. The shaft 78 is yieldingly urged to a stop position toward the right by a coil compression spring 86 similar to the spring 72.

The feed rolls 14 and 16 have frusto-conical knurled or lightly roughened working surfaces and are similar to the feed rolls already described in the above-mentioned Letters Patent No. 2,419,596.

Additional support for the presser roll shaft 36 is provided by bearings 85 and 87 secured in the brackets 82 and 50, respectively.

The seam ridge guide 18 consists of a pair of spaced members 88 and 90 (Figs. 7, 9 and 10) which engage opposite sides of the seam ridge. The member 88 is slidably mounted for lateral, i.e., right and left, adjustment upon the lower end portion of an arm 92 the upper end of which is pivotally mounted for lateral swinging movement upon a pin 94 (Fig. 8), conveniently in the form of a shoulder screw. The member 88 is secured in its position of lateral adjustment upon the arm 92 by a clamping screw 96. The member 90 is similarly secured by a shoulder screw 98, with provision for lateral adjustment, to a depending arm 100 which at its upper end is pivotally mounted for lateral swinging movement upon a shoulder screw 102 (Fig. 8). The screws 94 and 102 are both secured in opposite end portions of a bracket 104 which is slidably mounted for heightwise adjustment on a bracket 106 and which is secured in its adjusted position thereon by a clamping screw 107 passing through a heightwise slot 109 in the bracket 104. The screw 94 passes through a hole in the bracket 104, and the screw 102 passes through a slot 108 formed in the bracket 104 to enable the arm 100 to be adjusted heightwise relatively to the arm 92, both screws passing through washers bearing against the front face of the bracket and being secured by clamping nuts bearing against the rear face of the bracket. It is evident that with this arrangement the seam ridge guide members 88 and 90 may be adjusted to any desired height relatively to each other and also in unison with each other.

The bracket 106 is secured by a screw 103 (Fig. 2) upon an L-shaped bracket 110 (Figs. 1, 2 and 3). A tongue (not shown) depending from the bracket 106 and engaging a groove 105 (Fig. 3) in the bracket 110 provides for forward and rearward adjustment of the bracket 106 relatively to the bracket 110. The bracket 110 is slidably mounted for forward and rearward adjustment in a guideway 111 carried by the cross piece 28 and is secured therein in its adjusted position by a pair of clamping screws 112 passing through slots in the bracket 110 and threaded into the cross piece 28. The bracket 110 has a depending portion in which are formed slots 114 (Figs. 7 and 8) which serve as guideways for a limited lateral swinging movement of the arms 92 and 100 about their pivot screws 94 and 102, respectively. A cover plate 116 is secured by screws 118 upon the forward face of the depending portion of the bracket 110, the screws passing through heightwise elongated slots 120 formed in the cover plate to provide for its heightwise adjustment, for a purpose which will later be explained.

Both guide members 88 and 90 taper rearwardly from their supporting slides to a point close to the pressing roll 10, as shown in Figs. 9

and 10. The adjacent surfaces of these members are shaped to form a flaring work-receiving entrance between them. The work-engaging surfaces of the guide members gradually approach each other in the direction of progress of the work and become parallel to enable them to bear against the opposite sides of the seam ridge of the work piece W.

A pair of leaf springs 122 and 124 (Figs. 7 and 8) secured to the lateral edges of the bracket 110 and engaging the outer edges of the arms 92 and 100, respectively, below the bracket, yieldingly urge the guide members 88 and 90 toward each other. The lower portion of each spring is bent inwardly, as at 125, to engage its associated arm. The stiffness of these springs may be controlled by a pair of clamping plates 126 which partially cover the springs and which are secured by screws 128 with provision for heightwise adjustment to the bracket 110. It is evident that adjusting either of the plates 126 up or down will expose more or less of the effective portion of the spring which it controls and therefore vary the pressure of the spring against its associated arm. The purpose of the springs 122 and 124 is to press the arms 92 and 100 toward each other, thereby yieldingly holding the members 88 and 90 against opposite sides of the seam ridge of the work piece W. When there is no work in the machine, the arms 92 and 100 bear yieldingly against the inner edges of their guide slots 114, and they are shown in this position in Figs. 7 and 8. A clearance slot 129 for the seam rubbing roll 10 is cut into the depending portion of the bracket 110, as shown in Figs. 7 and 8.

The tab guide 24 (Figs. 8, 9 and 10) comprises a member 130 which is shaped approximately in the form of an inverted Y, having a stem portion and a pair of depending diverging branches, and it is pivotally mounted at a point somewhat above the junction of the stem and the branches upon a pivot pin 132 secured in the cover plate 116. The pin 132 may conveniently be a shoulder screw threaded into the cover plate. A boss 133 (Fig. 2), brazed on the member 130, provides a bearing for the member 130 on the pin 132. Heightwise adjustment of the member 130 is effected by adjusting the cover plate 116 up or down. Upon the lower end of the left-hand branch of the member 130 is secured, by a clamping screw 134, a work-engaging guide member 136 and upon the lower right-hand branch of the member 130 is secured, by a clamping screw 138, a work-engaging guide member 140. The freedom of swinging movement of the member 130 about its pivot 132 is limited by a pair of stops 142 and 144, which stops for convenience are secured in position upon the cover plate 116 by the lower pair of screws 118. The member 130 may be swung into either stop position at the will of the operator by mechanism comprising a rod 146 pivotally connected at its left-hand end to the upper end of the member 130 and at its right-hand end to an arm 148 (Fig. 1) extending upwardly from a shaft 150 (see also Figs. 3, 4 and 5) which is journaled in bearings mounted in the housing 68. Extending horizontally from the shaft 150 is an arm 152 (Fig. 1) to which is pivotally connected the upper end of a treadle rod 154 the lower end of which is pivotally connected to a treadle (not shown). A coil spring 156 surrounding the rod 154 and interposed between the upper surface of the base plate 34 and a collar 158 secured to the rod urges the rod upwardly and thus normally holds the member 130 yieldingly against the stop

142, with the left-hand work-engaging tab guide 136 in its operative position and the right-hand work-engaging tab guide 140 in an out-of-the-way position. By depressing the treadle, the operator can bring the member 130 against the stop 144 with the right-hand work-engaging member 140 in operative position and the left-hand member 136 in an out-of-the-way position. Both members 136 and 140 may be maintained in an out-of-the-way position by the use of a third or neutral stop 160 which is pivotally mounted upon a screw 161 threaded into the bracket 110 and extending through a heightwise clearance slot in the cover plate 116. The stop 160, which is engageable with a knob 162 on the upper portion of the member 130, is shown in Fig. 8 in its operative position against a stop pin 164; when its use is not desired it may be moved from this position by a finger piece 166 extending from the stop 160 to the left of the pivot screw 161. A coil compression spring 167 surrounding the shank of the screw 161 and interposed between the head of the screw and the stop 160 holds the stop frictionally against the face of the cover plate 116 to prevent undesired movement of the stop. It is evident that when the stop 160 is in its operative position the spring 156 will hold the tab guide 140 in a neutral position in which it straddles the work piece without touching it.

The work-engaging members 136 and 140 of the tab guide 24 are similar in shape, differing from each other only by reason of the fact that they are left- and right-hand members of a symmetrical pair. Each of these members consists of a downwardly extending portion 168 and a rearwardly extending portion 170, the portions 170 of the two members diverging from each other as they extend rearwardly. The work-engaging member 136 is shown in Figs. 9 and 10 operating upon the work piece W which, as has already been stated, is now inside out. In Fig. 9 the portion 168 of the member 136 is shown as engaging the under surface of the tab T of the work piece, the tab, as often happens, being curled back in the wrong direction with its finished surface up when the work piece is introduced to the machine. A smooth, rounded, continuous surface of the member 136 extends from the lower tip of the portion 168 to the rearward tip of the portion 170 and operates somewhat in the manner of a plow as the work piece advances to uncurl the tab and lay it down upon the opposite quarter with the finished surface of the tab down. Further advance of the work piece brings the tab under the feed roll 14, with the unfinished surface of the tab in engagement with the feed roll. Now, as the work piece advances, the feed roll will stretch the tab smooth and hold it down to present the unfinished surface of the tab to the presser roll 10. Any possibility of the finished surface of the tab being marred by the toothed work-engaging portion of the feed roll on the fluted periphery of the presser roll is thereby avoided.

The work support 12 consists of an assembly comprising a central disk 172 (Figs. 6 and 8) which presses the work upwardly against the roll 10, and a pair of side disks 174 and 176 which support the work against the pressure of the feed rolls 14 and 16. The disk 172 and the presser roll 10 constitute a pair of pressing members which cooperate to flatten the seam ridge. The disk 172 has a hub which is mounted upon a shaft 178 supported between a pair of spaced ears 180 carried by a square plunger 182 (Fig. 6). The disks 172 and 174 and 176 are similar to the cor-

responding disks already described and illustrated in Letters Patent No. 2,419,596.

The plunger 182 is slideable heightwise in a guideway formed in a block 184 (Figs. 1 and 6) which constitutes the upper end portion of a rearwardly inclined bracket 186 (see also Fig. 2). A block 187 (Figs. 1 and 6) secured against a lateral face of the block 184 retains the plunger 182 within its guideway. Housed within an axial bore in the plunger 182 is a coil compression spring 188 the lower end of which abuts against the upper end of a rod 190 which is rotatable and heightwise slideable in the block 184. The lower end portion of the rod 190 is threaded through an opening in a bracket 192. The degree of compression of the spring 188 may be adjusted by turning a knurled head 194 formed upon the lower end of the rod 190. The bracket 192 has an upwardly extending portion 196 which is slideable heightwise in a guideway formed in a cover plate 197. Both the block 187 and the cover plate 197 are secured to the block 184 by screws 199. The upper end of the portion 196 has a lateral extension 198 which hooks over a bar 200 secured to the plunger 182, the bar 200 serving to support the ears 190. The hook 198 thus limits the height to which the spring can yieldingly urge the work support. Freely rotatable in the bracket 192 is the smooth shank portion of a screw 202 which is threaded into a lower portion of the bracket 186. The bracket 192 is retained against heightwise movement relatively to the screw 202 by a collar 204 on the screw engaging the under surface of the bracket and a knurled head 206 on the screw engaging the upper surface of the bracket. The height of the hook 198 is determined by turning the head 206. A pointer 208 depending from the cover plate 197 may be used to register with graduations upon the upper surface of a dial or number plate 210 to determine the precise adjustment of the stop 198. The dial 210 is secured upon the top of the head 206 by a screw 209 in such position of angular adjustment as to bring the zero mark to whatever location has been found most suitable.

The bracket 186 has a base 212 (Figs. 1, 2 and 3) in the form of a horizontal dovetail slide which is guided for forward and rearward movement in a guideway formed by a pair of members 214 and 216 secured on the base plate 34. The beveled edges of the base or slide 212 are indicated on Fig. 3 by the numeral 218. A gib 215, which may be tightened by screws 217 (held by lock nuts), insures accurate bearing between the slide and its guideway. Secured to the rear edge of the slide 212 is a crossbar 220 (Fig. 3). A stop screw 222 threaded through a lug 224 upstanding from the base plate 34 engages the crossbar 220 to limit the rearward movement of the slide 212. The ends of the crossbar 220 extend laterally and beyond the sloping sides of the slide 212 and engage the rear ends of the guide members 214 and 216 to limit the forward movement of the slide. The slide may be shifted forwardly or rearwardly by the operator to its limiting positions. A spring detent 226 mounted in the guide member 214 engages notches 228 and 229 in the slide to retain the slide in its rearward and forward limiting positions, respectively. Each notch 228 and 229 has an inclined surface which cooperates with the spring detent by camming action to hold the slide yieldably in stop position without backlash.

When the work pieces consist of closed uppers, the slide 212 may be shifted forwardly to bring the work support away from the pressing roll and

the feed rolls and thus enable a stack of uppers which have accumulated around the work support to be removed from it. To facilitate such removal, a guard 230 (Fig. 2) extending from a rear surface of the bracket 186 to the seam-crease guide 22 is provided to keep the work from catching into any irregularities of the work support or the seam crease guide.

The forward seam-crease guide 20 is an upstanding blade-like member having a convex upper edge which initially centers the work piece for presentation to the operating instrumentalities and which supports the work immediately in advance of the work supporting disk 172. The guide 20 has a depending tip which engages a slot in the disk 172 to stiffen the guide against lateral displacement. The guide 20 is secured within a slot in a bracket 232 (Figs. 1 and 2) by clamping screws 234 which pass through enlarged holes in the guide to permit slight adjustment. The lower portion of the bracket 232 is slidably mounted for heightwise adjustment on a guide 236 secured to and depending from the bar 200. A clamping screw 238 passing through a slot in the bracket 232 maintains the bracket in any desired position of heightwise adjustment. The rear seam-crease guide 22 is similar to the forward guide 20, and is similarly supported, with provision for heightwise adjustment, by the bar 200. It supports the work piece immediately in the rear of the disk 172. The guides 20 and 22, being carried by the plunger 182, are adjusted heightwise in unison with the disks 172, 174 and 176 by turning the screw head 206.

35 The machine above described may be used for pressing the seams of open as well as of closed uppers. It is convenient, when a batch of treated open uppers has accumulated, to tie them together with a string upon removing them. To facilitate such handling of open uppers, the illustrated machine is provided with a support 240 (Figs. 1, 2, and 3) upon which the treated uppers may drop. This support consists of an M-shaped piece of sheet metal which straddles the slide 212 (when the slide is in operating position) and which is secured to the base plate 34 by screws 242 passing through flanges 244 extending laterally from the member 240. The support 240 has a V-shaped central trough, extending forwardly and rearwardly, which holds the string straight and in a convenient position. The use of this device saves considerable time and trouble in tying together the batch of treated uppers.

To prevent fuzz from adhering to the periphery of the pressing roll 10, there is provided a felt wiper 246 (Fig. 2) supported by a leaf spring 248 secured to the cross piece 28 of the frame. The spring 248 holds the wiper 246 yieldingly against the periphery of the pressing roll.

60 The frame 26 is designed with particular regard to the convenience of the operator in handling the work. The side members 30 and 32 are positioned far enough apart to afford access for the operator's hands on each side of the work support. To insure ample freedom in manipulating the work and in removing batches of treated open uppers, the members 30 and 32 are not only spaced well apart, but their base portions, as shown in Figs. 2 and 3, are positioned well to the rear of the work support 12, the locality of operation, and the axis of the presser roll 10. The cross piece 28 is inclined in a plane at right angles to the axis of the plunger 182, the inclination of these parts being so chosen as to bring the bite 70 of the presser roll 10 and the supporting disk 172

tangent to the operator's line of sight, thereby affording him a clear view of the work piece during the operation. To insure against flexing of the presser roll shaft 36 and the feed roll shafts 44 and 78 under pressure of the work, the cross piece 28 has an upstanding integral stiffening flange 250.

The operation of the illustrated machine will be evident from the above description. The slide 212, if not already in its normal or operating position, is moved rearwardly until stopped by the screw 222 and latched by the detent 226 in the notch 228. If the work is of the ordinary kind, without Hurley back stay tabs, the treadle is depressed to shift the knob 162 out of the way of the neutral stop 160 and the neutral stop 160 is moved down into operative position. The treadle is then released to permit the spring 156 to hold the tab guide 24 in neutral or inoperative position with the knob 162 against the stop 160. When thus maintained in neutral position, the tab guide 24 does not obstruct the view and, furthermore, it is out of the way of certain types of work, such as high uppers having seams of re-entrant curvature as they extend upwardly of the shoe. Such uppers might otherwise, by reason of the curvature of their seams, come into undesirable contact with the tab guide.

The operator then introduces the work piece W, flesh side up, over the guide 20, with the guide engaging the seam crease. The upstanding seam ridge is then received within the flaring opening between the ridge guide members 88 and 90. The operator thus advances the work piece by hand until it is gripped by the feed rolls 14 and 16. The operation of the presser roll 10, the feed rolls 14 and 16, and the work supporting disks 172, 174 and 176 is similar to that of the corresponding members of the machine disclosed in Patent No. 2,419,596 above referred to. The ridge guide members 88 and 90 of the present machine, being yieldable laterally rather than heightwise, may be extended back close to the bite of the presser roll 10 and the supporting disk 172 without danger of striking the presser roll; they are thereby enabled to control the work piece almost up to the locality of operation. The rear seam crease guide 22, which is new in the present machine, assists the forward guide 20 in keeping the work piece centered, and it also supports the work piece as it is leaving the locality of operation and overcomes any tendency of the work piece to sag and thereby tilt up its trailing end against the rapidly rotating presser roll with possible danger of damage to the work piece.

If the work consists of closed uppers, the work pieces, after passing through the operating instrumentalities, drop from the rear guide 22 and stack up around the work support bracket 186. When a batch of uppers has thus accumulated, the operator pulls the slide 212 forward until it is latched by the detent 226 in the notch 229, and then removes the batch by lifting it up over the work support 12 and the crease guides 20 and 22. If, on the other hand, the work consists of open uppers, a string will be laid in the trough of the member 240 before beginning the operation. The treated work pieces will drop off the guide 22 and will stack up on the member 240, from which they may be removed without shifting the slide 212. Upon removing the batch of stacked uppers they may readily be tied together with the string.

If the work pieces have Hurley back stay tabs, the neutral stop 160 should be shifted up to its

out-of-the-way position. The spring 156 will then normally hold the tab guide 24 against the stop 142 with the guide member 136, as shown in Figs. 9 and 10, in its operative position for tabs extending toward the left. For work pieces having tabs extending toward the right, the treadle should be held depressed to maintain the tab guide against the stop 144 with the guide member 140 in its operative position.

Having described our invention, what we claim as new and desire to secure by Letters Patent of the United States is:

1. In a machine for pressing the ridge of a seam joining the back quarters of a shoe upper of which one of the quarters has a tab extending above the seam ridge, a guide engageable with the tab as the work piece progresses to the pressing instrumentalities, said guide being constructed and arranged to lay the tab down over the other quarter to avoid exposure of the finished surface of the tab during further progress of the work.
2. In a machine for pressing the ridge of a seam joining the back quarters of a shoe upper of which one of the quarters has a tab extending above the seam ridge, a guide engageable with the tab as the work piece progresses to the pressing instrumentalities, said guide being constructed and arranged to lay the tab down over the other quarter to avoid exposure of the finished surface of the tab during further progress of the work, and a support upon which said guide is mounted for movement between operative and out-of-the-way positions.
3. In a machine for pressing the ridge of a seam joining the back quarters of a shoe upper of which one of the quarters has a tab extending above the seam ridge, a guide engageable with the tab as the work piece progresses to the pressing instrumentalities, said guide being constructed and arranged to lay the tab down over the other quarter to avoid exposure of the finished surface of the tab during further progress of the work, a support upon which said guide is mounted for movement between operative and out-of-the-way positions, resilient means for yieldingly holding said guide in one of said positions, and treadle-operated means for moving the guide into the other position.
4. In a machine for pressing the ridge of a seam joining the back quarters of a shoe upper of which one of the quarters has a tab extending above the seam ridge, means for laying the tab down over the other quarter to avoid exposure of the finished surface of the tab during further progress of the work, and a support for said laying means constructed and arranged to permit movement of the laying means between two positions, said positions being such as to enable the laying means to operate upon tabs extending from right and left quarters respectively.
5. In a machine for pressing the ridge of a seam joining the back quarters of a shoe upper of which one of the quarters has a tab extending above the seam ridge, a pair of guides, one of said guides being engageable with a tab extending from the right quarter of an upper to lay that tab down over the left quarter to avoid exposure of the finished surface of the tab during further progress of the work, the other guide being engageable with a tab extending from the left quarter of a different upper to lay that tab down over the right quarter for presentation to the pressing instrumentalities, and a support constructed and arranged for movement of said guides to bring

either guide into its operating position while moving the other guide out of its operating position.

6. In a machine for pressing the ridge of a seam joining the back quarters of a shoe upper of which one of the quarters has a tab extending above the seam ridge, a pair of guides, one of said guides being engageable with a tab extending from the right quarter of an upper to lay that tab down over the left quarter to avoid exposure of the finished surface of the tab during further progress of the work, the other guide being engageable with a tab extending from the left quarter of a different upper to lay that tab down over the right quarter to avoid exposure of the finished surface of the tab during further progress of the work, and means for moving said guides to bring each guide into its operating position and simultaneously to move the other guide out of its operating position.

7. In a machine for pressing the ridge of a seam joining the back quarters of a shoe upper of which one of the quarters has a tab extending above the seam ridge, a guide, a second guide, a support on which said guides are mounted in fixed relation to each other, and means for moving said support between two positions, in one of which positions the first-mentioned guide is engageable with a tab extending from the right quarter of an upper to lay that tab down over the left quarter to avoid exposure of the finished surface of the tab during further progress of the work and the second-mentioned guide is out of the way, and in the other position the second-mentioned guide is engageable with a tab extending from the left quarter of a different upper to lay that tab down over the right quarter to avoid exposure of the finished surface of the tab during further progress of the work and the first-mentioned guide is out of the way.

8. In a machine for pressing the ridge of a seam joining the back quarters of a shoe upper of which one of the quarters has a tab extending above the seam ridge, a pair of guides, one of said guides being engageable with a tab extending from the right quarter of an upper to lay that tab down over the left quarter to avoid exposure of the finished surface of the tab during further progress of the work, the other guide being engageable with a tab extending from the left quarter of a different upper to lay that tab down over the right quarter to avoid exposure of the finished surface of the tab during further progress of the work, means for holding each guide in its operating position while holding the other guide in an out-of-the-way position, and means for simultaneously holding both guides in out-of-the-way positions when the machine is to operate upon a work piece without a tab.

9. In a machine for pressing the seams of closed uppers of shoes and having a pressing member engageable with a work piece from above, and a cooperating pressing member normally beneath the first-mentioned pressing member and engageable with the underside of the work piece, said machine being constructed and arranged to enable each work piece at the completion of an operation to fall around the second-mentioned pressing member with the second-mentioned pressing member extending through the central opening of the closed upper, a slide upon which the second-mentioned pressing member is mounted and a guideway in which said slide is movable horizontally to bring the second-mentioned pressing member out from under the first-

mentioned pressing member to a position convenient for the removal of a batch of treated closed uppers from around the second-mentioned pressing member.

10. In a machine for pressing the seams of closed uppers of shoes and having a pressing member engageable with a work piece from above, a cooperating pressing member normally beneath the first-mentioned pressing member and engageable with the underside of the work piece, and a support for the second-mentioned pressing member adjustable heightwise to vary the position of the second-mentioned pressing member toward and from the first-mentioned pressing member, said machine being constructed and arranged to enable each work piece at the completion of an operation to fall around the second-mentioned pressing member and the support with the support extending through the central opening of the closed upper, a slide upon which the second-mentioned pressing member is mounted, and a guideway in which said slide is movable horizontally to bring the second-mentioned pressing member and the support out from under the first-mentioned pressing member to a position convenient for the removal of a batch of treated closed uppers from around the support.

11. In a machine for pressing the seams of closed uppers of shoes and having a rotary rubbing tool engageable with a seam ridge upstanding from a work piece, a work support normally beneath said rubbing tool and engageable with the underside of the work piece, and work feeding means, said machine being constructed and arranged to enable each work piece at the completion of an operation to fall around the work support with the work support extending through the central opening of the closed upper, a slide upon which the work support is mounted, and a guideway in which said slide is movable forwardly to bring the work support to a position convenient for the removal of a batch of treated closed uppers from around the work support.

12. In a machine of the class described, a work support, a base on which said work support is mounted, a rotary tool for operating on a work piece on said work support, a shaft on which said tool is mounted, means for driving said shaft, a pair of feed rolls engageable with the work piece at opposite sides of said tool, a pair of shafts upon which said feed rolls are respectively mounted, gearing between each of the feed roll shafts and the tool shaft for driving the feed roll shafts, a pair of side frame members extending upwardly from said base on opposite sides of the work support and having their lower portions spaced laterally and also rearwardly of the work support to afford access for the hands of the operator in manipulating the work, a cross frame member carried by said side frame members, bearings for said tool shaft and for said feed roll shafts carried by said cross frame member adjacent to the locality of operation, and other bearings for said shafts supported by the frame members remote from the locality of operation.

13. In a seam pressing machine, a support for a work piece having an upstanding seam ridge, a tool for pressing the seam ridge of the work piece on the work support, means for feeding the work piece past said tool, and a blade-like member positioned rearwardly of the locality of operation for centering the work piece in its passage past the tool and for supporting the work piece as the work piece passes from beneath the

13

tool and the work support to prevent upward tilting of the trailing end of the work piece.

14. In a seam pressing machine, a disk-shaped member having its periphery adapted to support a work piece having an upstanding seam ridge, a tool for pressing the seam ridge of the work piece on the work support, means for feeding the work piece past said tool, and a pair of blade-like members positioned forwardly and rearwardly of the locality of operation for centering the work piece in its passage past the tool, the rear blade-like member serving also to support the work piece as the work piece passes between the tool and the work support to prevent upward tilting of the trailing end of the work piece.

15. A seam pressing machine comprising a work supporting element, a pressing tool cooperating with said work supporting element to press the seam ridge of a work piece, a plunger on which said work supporting element is mounted, a guide in which said plunger is mounted for movement of the work supporting element toward and from said pressing tool, a stop for limiting the movement of the work supporting element toward the pressing tool, a slide on which said stop is mounted, a guideway in which said slide is movable to vary the position of the stop and thereby the limiting position of the work supporting element to-

14

ward and from the pressing tool, an extension on the slide, an abutment on said extension, a spring interposed between said abutment and the plunger to urge the plunger and the work supporting element toward the pressing tool as far as permitted by said stop, an adjustable connection between the abutment and the extension to enable the stress of the spring to be adjusted without varying the position of the stop, and means for adjustably securing the slide in a desired position in its guideway to enable the limiting position of the work support to be adjusted toward and from the pressing tool without varying the stress of the spring.
